Fig. 1: A front view of the curtain assembly (A) mounted on a vertical support (B) within a rectangular frame. The support (B) is attached to a base (k) which contains a grate (l). The assembly is shown in an open position, with the horizontal slats (B) visible.

UNITED STATES PATENT OFFICE.

WILLIAM H. BURDEN, OF CLEVELAND, OHIO.

CURTAIN BLOWER FOR GRATES OR STOVES.

SPECIFICATION forming part of Letters Patent No. 542,302, dated July 9, 1895.

Application filed November 1, 1894. Serial No. 527,680. (No model.)

To all whom it may concern:

Be it known that I, WILLIAM H. BURDEN, a citizen of the United States, and a resident of Cleveland, county of Cuyahoga, and State of Ohio, have invented certain new and useful Improvements in Curtain Blowers for Fire-Grates or Stoves, of which the following is a specification.

This invention relates to blowers for grates, stoves, and similar fireplaces; and it consists of an automatically-operating slatted curtain arranged in front of a stove or fireplace, substantially as hereinafter described, and pointed out in the claim.

15 In the accompanying drawings, Figure 1 is a front elevation of a grate or fireplace having my improved curtain attached. Fig. 2 is a vertical section of the same. Fig. 3 is a rear side view of the slatted curtain, showing the 20 method of attaching the slats to the supporting-chains. Fig. 4 is a rear side view of a curtain composed of asbestos. Fig. 5 is a sectional view of a portion of the slatted curtain, showing the manner of attaching the slats to 25 the chain.

A represents a mantel and grate-front, which may be of any of the well-known patterns and styles, or instead of a mantel it may be an open stove-front, as my improvement 30 is applicable to either.

B is an automatic spring curtain-roller suitably attached to the front A above the fireplace-opening.

C is a curtain composed of metal-slats supported on two or more chains D. The slats are loosely attached by means of headed rivets d, inserted through the links of the chains. This allows the slats to adjust themselves laterally, and also avoids binding of the slats to

one another or to the links in case of heating 40 and warping.

E are guide-rollers attached to the sides of the grate for the purpose of holding the curtain close to the grate and to prevent its swinging outward. Suitable knobs h may be 45 attached to the lower slat for the purpose of operating the curtain.

m m are openings in the upper slots for the purpose of opening a draft to the upper part of the grate when the curtain is drawn down 50 to the hearth, shutting off under-draft.

In Fig. 4 a different form of chain is shown as attached to a curtain made of asbestos fabric as a substitute for the slats.

F is a hood attached to the front A for covering and concealing the roller B and curtain C when rolled up.

From the foregoing it will be seen that this improved curtain-front is very easily operated and may be adjusted at any height to close 60 the grate-front opening and that it is very efficient for preventing the escape of dust, soot, or smoke—the terrors of the cleanly housewife.

Having described my invention, what I 65 claim, and desire to secure by Letters Patent, is—

The herein described curtain blower for grates, consisting of chains D, slats C attached to said chains with rivets d loosely inserted 70 through the links of the chain and permanently fixed in the slats, in combination with the spring roller B and adapted to operate as described.

WILLIAM H. BURDEN.
